UNITED STATES PATENT OFFICE

2,489,990

FLOORING JACK

Thomas Treaster, San Francisco, Calif.

Application May 22, 1946, Serial No. 671,512

2 Claims. (Cl. 254—12)

1

This invention relates to improvements in flooring jacks used in laying flooring boards.

An object of the invention is to provide an improved flooring jack used in laying flooring, to assure tight joints between adjacent floor boards.

Another object of the invention is to provide an improved flooring jack used in laying floors, the same being positively clamped to a floor joist and having a pusher head engageable with the edge of a board being laid.

A further object of the invention is to provide an improved flooring jack used in laying floors, the same being adapted to be clamped to a floor joist and having a pusher head engageable with an edge of a floor board being laid, together with a rack and pinion means for forcing the head forwardly to push the floor board tightly in place, and means for locking the rack and pinion and said head in projected position.

A still further object of the invention is to provide an improved flooring jack which will be highly efficient in use, and relatively inexpensive to manufacture and produce.

Other objects will appear as the description proceeds.

In the accompanying drawings which form a part of this application,

Figure 1 is a perspective view of the improved flooring jack showing the same in position while laying a floor;

Figure 2 is a vertical sectional view taken on the line 2—2 of Figure 1;

Figure 3 is a top plan view of the floor jack the same being shown partially in section to illustrate the jack operating means;

Figure 4 is a bottom plan view of the floor jack, partially in section to show the means for securing the rack bar to the head piece;

Figure 5 is a sectional view taken on the line 5—5 of Figure 2;

Figure 6 is a sectional view taken on the line 6—6 of Figure 3;

Figure 7 is a sectional view taken on the line 7—7 of Figure 3;

Figure 8 is a detailed sectional view taken on the line 8—8 of Figure 3, and

Figure 9 is a perspective view of a modified tail piece having attaching spurs for engagement with a sub-floor.

Like characters of reference are used throughout the following specification and the accompanying drawing to designate corresponding parts.

In carrying out the invention there is provided an improved form of floor jack used in laying

2

floors and comprising a head member generally denoted by the reference numeral 1 formed with an elongated floor board edge engaging block 2, and a cold rolled steel plate 3 secured by the screw fasteners 4 to said block adapted to overlie the floor board 5 being laid and to contact the upper surface thereof.

A pair of parallel spaced toothed racks 6 and 7 are provided with the threaded terminal 10 fastening studs 8 and 9 adapted to be received in the internally threaded sockets 10 and 11 formed in the adjacent edge of the block 2, to be movable as a unit with said block. A connecting plate 50 is disposed between said racks 6 and 7, and is secured to the bottoms thereof by the screws 55.

The tail member of the floor jack is generally designated by the reference numeral 12, and includes an elongated block 13 to which the cold rolled steel plate 14 is secured by means of the screw fasteners 15. The plate 14 is formed at one end with the integrally formed depending flange 16 having spurs 17 attached to its base, and adapted to be embedded in the side of a floor stud or joist 18 when the jack is in position as shown in Figure 1 of the drawings.

An eccentric clamp having a cam head 19 is pivotally supported upon the pivot pin 20 extending through the plate 14, and is provided with the operating handle 21, said cam clamp being positioned immediately below said plate 14.

In the event the jack is to be used in laying floors over a sub-floor 22, where the floor joists 18 are not exposed, the plate 23 shown in Figure 9 of the drawings will be used, and is provided with the sub-floor engaging spurs 24, and is not provided with any form of end flange construction.

A stationary block 25 is adapted to extend between the two toothed racks 6 and 7 and to be secured by the threaded member 26 to the block 13, and is formed at its forward end with the arcuate pinion supporting head 27 in which locking teeth 28 are formed.

A pair of offset depending spaced pinion sections 29 and 30 are pivotally mounted on the pivot pin 31 extending through the stationary head 27, and are also connected together by the pin 32 upon which the locking pawl or dog 40 is pivotally mounted for engagement and cooperation with the locking piece 28 formed on the said head 27. The upper ends of the pinion sections 29 and 30 are secured together to form the socket 33, in which the detachable jack operating handle 34 is adapted to be received.

From the foregoing description it is believed

that the mode of operation will be apparent. When flooring is to be laid directly on floor joists, the eccentric clamp will be secured to a floor joist and the head of the jack brought into engagement with the edge of the floor board being laid, after which the handle 34 is moved to cause the pinion sections 29 and 30 to move the racks 6 and 7 and the interconnected head forwardly to force the floor board tightly against the previously laid board. Nails will then be driven into the board while the jack is holding it in place. The pawl or dog 32 serving to hold the jack in adjusted position while the securing nails are being driven home.

When a floor is to be laid over a sub-floor, the tail piece with spurs shown in Figure 9 of the drawings will be used by driving the spurs into the sub-flooring to locate and hold the jack.

While the preferred embodiment of the invention has been illustrated and described it will be understood that it is not intended to limit the scope of the invention thereto, as many minor changes in detail of construction may be resorted to without departure from the spirit of the invention.

Having thus described my invention what I claim as new and desire to secure by Letters Patent of the U.S. is:

1. A floor laying jack comprising a floor board engaging member, a pair of spaced parallel track bars carried by said floor board engaging member, a connecting plate underlying and secured to the track bars, an anchor member, means carried by said anchor member for engaging a floor joist, means for actuating said floor joist engaging means into engagement with a floor joist, a stationary support member carried by the anchor member and disposed between the track bars, said support member resting upon said connecting plate, a head carried by said support member having locking teeth, a pair of pinion sections pivoted on said head for engaging said track bars,

10
15
20

and a pawl pivotally mounted between said pinion sections for engaging the locking teeth of said head.

2. A floor laying jack comprising a floor board engaging block, a bearing plate carried by said block for engaging the top surface of a floor board, a pair of spaced parallel track bars carried by and movable with said floor board engaging block, a connecting plate underlying and secured to said track bars, an anchor member including a base plate having a depending flange at one end, a holding block carried by said base plate, a stationary block carried by said holding block and disposed between said track bars, said stationary block resting upon said connecting plate, a head rising from said stationary block having locking teeth, a pair of pinion sections pivotally carried by said head and engaging said track bars, a pivot pin carried by said pinion sections, a pawl pivotally mounted on said pin engaging the locking teeth of said head, spurs carried by the flange of said base plate for engaging a floor joist, and means carried by said plate for forcing said spurs into a floor joist.
